UNITED STATES PATENT OFFICE

MILTON ALDEN, OF SPRINGFIELD, MASSACHUSETTS, ASSIGNOR, BY MESNE ASSIGNMENTS, TO ROBERT S. ALLYN, OF NEW YORK, N. Y.

SUPPORT FOR VACUUM TUBES

Application filed August 12, 1926. Serial No. 128,725.

This invention relates to an improvement in supports for vacuum tubes for use in radio apparatuses, and has for its object to provide a support of simple construction capable of reducing to a minimum the shocks and vibrations that may be transmitted from outside sources through the support to the delicate mechanism of the vacuum tube, said shocks and vibrations often tending to reduce 10 the efficiency of said tube and interfere seriously with its operations.

It is still further an object of the invention to embody in the structure of the support a plurality of springs, each of which is 15 preferably constructed of a continuous length of wire and has a helical compression portion formed integral therewith for encircling the terminal pins of the vacuum tube, said spring constituting electric circuit connections to said pins and tube.

Still another object of the invention is to embody in the construction of the supporting springs a loop which is utilized in securing the support to its base, and in interposing 25 between said loop and the compression portion of the spring a torsion coil, the axis of said torsion coil being at right angles to the axis of said loop and compression portion.

Another object is to prevent distortion of 30 the spring members when inserting or removing a tube.

The invention consists in a support for a vacuum tube as set forth in the following specification and particularly as pointed out 35 in the claims thereof.

Referring to the drawings:

Figure 1 represents a central vertical section through a vacuum tube support embodying my invention, a vacuum tube of well-known type being mounted upon said support.

Figure 2 is an underneath plan view of the support.

Figure 3 is a central vertical section illustrating a modified embodiment of my invention.

Figure 4 is a central vertical section illustrating still another modified embodiment 50 of the invention.

Like numerals refer to like parts throughout the several views of the drawings.

In the drawings, referring particularly to Figs. 1 and 2, 10 represents a panel constituting a base and constructed of suitable insulating material. Located above the base 10 is an insulating member 11, preferably cylindrical in form and also constructed of insulating material. The insulating member 11 is provided with a plurality of openings 12 extending downwardly therethrough, said openings being provided for the purpose of receiving the terminal pins *a* of a vacuum tube A, and said openings may be of different diameters as illustrated in Figs. 1 and 2, or they may all be the same diameter without departing from the spirit of the invention, it being evident that it is necessary to form and position the openings to correspond to the size and location of the terminal pins provided upon the different types of vacuum tubes.

The insulating member 11 is yieldingly supported above the base 10 by a plurality of springs 13, each of which is constructed of a continuous length of wire and embodies therein a helical portion 14 constituting a compression coil, the upper portion of which is fastened to the insulating member 11 around the openings 12, and preferably said helical portion is imbedded in the material of the insulating member and the inner diameter of said helical portion is the same diameter as that of the terminal pins *a*. The springs 13 furthermore constitute electric circuit connections to the vacuum tube A and the diameter of the compression coil 14 of said spring is such that when the terminal pins *a* of said vacuum tube A are inserted therein, the convolutions of the coil 14 will snugly engage the periphery of the terminal pins and form an electrical contact therewith.

The springs 13 embody therein an intermediate portion 15 which projects laterally from the lower end of the helical portion 14 thereof, and said intermediate portion is approximately parallel with the upper surface of the base 10 and has a torsion coil 16 formed therein, the axis of which is preferably located at right angles to the axis of the com-

pression coil 14. The springs 13 also embody therein a loop 17 which is utilized in securing the support to the panel 10, and said loop is formed with its axis perpendicular to the base 10 and parallel to the axis of the compression coil 14.

A binding post 18 is employed as a fastening member in securing the support to the base 10, and said binding post extends 10 through the loop 17 and base 10 and may have a connecting wire attached thereto in the usual well-known manner, if it is so desired. Each loop 17 has a terminal portion 19 projecting therefrom and extending downwardly through an opening 20 provided in the base 10, said terminal being provided for the purpose of having a connecting wire attached thereto in any desired manner.

In Figure 3 I have illustrated a modified 20 embodiment of my invention in which the insulating member 11 is supported upon the base 10 by a plurality of springs 21, each of which constitutes an electric circuit connection to a vacuum tube and embodies therein 25 a helical portion 22 constituting a compression coil, an intermediate portion 23 having a torsion coil 24 formed therein, and a loop 25; but in this spring, a portion 26, between the loop 25 and torsion coil 24, is 30 curved upwardly from said loop toward said coil, and the latter is located about midway between the loop 25 and the compression coil 22.

The spring 21 is fastened to the base 10 35 by a binding post 28 which extends through the loop 25 of said spring, and said binding post may have a connecting wire attached thereto in the usual well-known manner. Each loop 25 has a terminal portion 27 projecting therefrom and extending downwardly through an opening provided in the base 10, said terminal being provided for the purpose of having a wire attached thereto, if it is so desired.

45 In Figure 4 still another embodiment of the invention is illustrated in which the insulating member 11 is supported upon the base 10 by a plurality of springs 29, each of which constitutes an electric circuit connection to a vacuum tube and embodies therein 50 a helical portion 30 constituting a compression coil and an intermediate portion 31, at one end of which is a torsion coil 32. From the torsion coil 32 of the spring 29, a portion 55 33 extends approximately parallel to the intermediate portion 31 and said portion 33 terminates in a loop 34 which is located beneath the insulating member 11. The spring 29 is fastened to the base 10 by a binding post 60 35 which extends through the loop 34 and the latter has a terminal portion 36 projecting therefrom and extending downwardly through an opening 37 provided in the base 10.

65 Preferably I provide means for limiting

the movement of the top piece 11 so as to prevent injury to the springs such as a screw 38 passing through the aperture 41 and is secured firmly into the threaded hole in the metallic insert 40 said insert being moulded or imbedded into the insulating member 11. This construction functions as a stop in upward direction thus preventing injury to the shock absorbing springs during the removal of the vacuum tube.

70 Upon the screw 38 may be placed a threaded collar 39 which when inserting the A tube in the socket or insulating member 11 may engage the base 10 thus limiting the downward movement of said insulating member 11 thus preventing injury to the springs 13, 21, or 29.

75 The use of this limiting member is optional and is more desirable in some embodiments of my invention than in others.

80 The various embodiments of this invention are all employed in exactly the same manner as supports for vacuum tubes, and said supports, by reason of their yielding construction, absorb the shocks and vibrations transmitted thereto and prevent injury to the delicate mechanism of the vacuum tube, and the translation of mechanical vibrations of the tube into electrical vibrations in its associated 85 circuits.

90 In each of the embodiments of the invention, the springs that are employed in yielding supporting the insulating member are all utilized as electric circuit connections to the terminal pins of the vacuum tube, and while it is preferable to have the helical portion of said springs encircle and engage the terminal pins of said vacuum tube, it is evident that said spring may engage the terminal pins without encircling the same.

95 While the various embodiments of this invention all embody therein a torsion coil and a compression coil, it is evident that the helical portion that forms the compression coil 100 may be wound with the convolutions thereof engaging with each other and in a manner to engage the terminal pins *a* of the vacuum tube and form a contact therewith, as it is evident that the construction of the spring is such that it will form an efficient yielding 105 support for the insulating member 11 even though the compression action of the spring is eliminated.

110 I claim:

115 1. A support for a vacuum tube or the like comprising, in combination, a base, an insulating member, a plurality of springs yielding 120 supporting said insulating member upon said base, each of said springs embodying therein a torsion coil and a compression coil, the latter being fast to said insulating member and adapted to engage a terminal of a vacuum tube, said spring constituting an 125 electric circuit connection thereto, and means to fasten each of said springs to said base. 130

2. A support for a vacuum tube or the like comprising, in combination, a base, an insulating member, a plurality of springs yieldingly supporting said insulating member upon said base, each of said springs embodying therein a torsion coil and a compression coil, the latter being fast to said insulating member and adapted to engage a terminal of a vacuum tube, said spring constituting an electric circuit connection thereto, each of said springs also embodying therein a loop, and means extending through each of said loops and securing each of said springs to said base. 70
- 15 3. A support for a vacuum tube or the like comprising, in combination, a base, an insulating member, a plurality of springs yieldingly supporting said insulating member upon said base, each of said springs embodying therein a torsion coil and a compression coil, the latter being fast to said insulating member and adapted to encircle the terminal of a vacuum tube, said spring constituting an electric circuit connection thereto, each of said springs also embodying therein a loop having a terminal portion projecting therefrom, and means extending through each of said loops and securing each of said springs to said base. 75
- 20 4. A support for a vacuum tube or the like comprising, in combination, a base, an insulating member, a plurality of springs yieldingly supporting said insulating member upon said base, each of said springs embodying therein a torsion coil and a compression coil, the latter being fast to said insulating member and adapted to encircle the terminal of a vacuum tube, said spring constituting an electric circuit connection thereto, each of said springs also embodying therein a loop, the median line of said torsion coil extending transversely of the median lines of said loop and compression coil, and means extending through each of said loops and securing each of said springs to said base. 80
- 25 5. A support for a vacuum tube or the like comprising, in combination, a base, an insulating member, a plurality of springs yieldingly supporting said insulating member upon said base, each of said springs embodying therein a torsion coil and a compression coil, the latter being fast to said insulating member and adapted to encircle the terminal of a vacuum tube, said spring constituting an electric circuit connection thereto, each of said springs also embodying therein a loop, the axes of said loop and compression coil being perpendicular to said base and the axis of said torsion coil being parallel to said base, and means extending through each of said loops and securing each of said springs to said base. 85
- 30 6. A support for a vacuum tube or the like comprising, in combination, a supporting base, a plurality of conducting and shock 90
- 35 95
- 40 100
- 45 105
- 50 110
- 55 115
- 60 120
- 65 125
